UNITED STATES PATENT OFFICE.

THOMAS J. McDONALD, OF BLUE RIDGE, GEORGIA.

STEAM-GENERATOR.

1,381,481.

Specification of Letters Patent. Patented June 14, 1921.

Application filed July 19, 1920. Serial No. 397,216.

To all whom it may concern:

Be it known that I, THOMAS J. McDONALD, a citizen of the United States, residing at Blue Ridge, in the county of Fannin and State of Georgia, have invented new and useful Improvements in Steam-Generators, of which the following is a specification.

The present invention relates to improvements in steam generators and is particularly designed for such generators as are employed with motor vehicles.

The particular object of the invention is to provide a generator of the type referred to, which will be relatively light in weight, compact and the parts of which may be readily removed and replaced if desired. A further object of the invention is to provide such a generator with a maximum amount of surface exposed to the heating means, whereby the generation of steam may be very rapidly effected.

In the accompanying drawings:

Figure 1 is a vertical sectional view through a generator embodying the invention, such section being taken substantially on the line 1—1 of Fig. 2;

Fig. 2 is a plan with the outer casing or cover for the generator removed.

Referring to the drawings, 1 designates a main or central heating chamber which is provided at its lower end with a water inlet 2 and has a steam outlet 3 at its upper end. At suitable intervals the central chamber 1 is provided with a plurality of series of lateral ports 4, which are connected with circulating tubes that will be hereinafter more particularly referred to.

The chamber 1 is preferably formed of a single tube and adjacent its lower end has formed thereon an exterior annular flange or abutment 5.

The chamber 4 is surrounded by a plurality of independently removable units, each comprising an inner or central sleeve 6, an outer annular tubular member 7 and a series of intermediate connected pipes or tubes 8. The sleeves 6 of the several units are slipped over the chamber 1 and said sleeves are held in close contact with each other and with the flange or abutment 5 by means of a nut 9 which is fitted over the chamber 1 and engaged with a suitable thread 10 formed thereon.

The tubes 8 of each unit are preferably welded to the sleeves 6 and outer members 7 and the passages in said sleeves with which

said tubes are in communication with the ports 4 in the side wall of the central chamber 1. Means that will be hereinafter more particularly described are provided by which water will be returned from the annular, tubular member 7 of each unit to the lower end of the chamber 1 so that the desired circulation through the generator may be maintained.

In the particular embodiment of the invention illustrated, each tubular member 7 is provided with four outwardly extending tubes 11, which at their outer ends are connected with sleeves 12 that surround a tubular header 13 which is connected with the lower end of the central header or chamber 1 by pipes 14. The outer headers 13 are generally similar to the member constituting the central chamber 1 being closed at both ends and the sleeves 12 are maintained in proper position thereon by nuts 15, generally similar to the nut 9, before referred to. The headers 13 serve as a means for supporting the generator on a suitable frame, brackets 16 being shown as arranged directly beneath them.

Preferably the meeting ends of the several sleeves, 6, 12, are of the form shown so that they will overlap one another and suitable packing rings 17 are preferably arranged between the end portions immediately adjacent the connecting header or tube so that escape of steam or water from the generator is effectually prevented.

Preferably the generator is inclosed within a suitable casing 18 and is supported by the brackets 16 above a vapor burner or other source of heat 19.

The several parts may be formed of any suitable material, the central header or chamber 1 being formed from a single tube which is closed at the ends except for the water inlet and steam outlet and it will be seen that the water introduced into such chamber will be caused to circulate radially outward through the tubes 8 into the annular chamber 7 and from such chambers through the tubes 11 outer headers and return pipes 14. By this means the water is divided into a relatively large number of small bodies, in passing through the tubes 8, all of which are exposed to the heat rising from the burner 19. The steam generated in the lower heating units will be superheated in passing through the upper units and by the construction shown and

hereinbefore described it is possible to very quickly generate steam of a very high pressure. The tubes radiating from the central header or chamber 1 are all inclined downward as are also the tubes 11 connecting the annular chambers 7 and the outer sleeves 12 which facilitates the circulation.

As above stated, it is preferred to connect the several tubes to the sleeves and chambers by welding but, of course, there can be modification in this respect if desired. Also while the drawings illustrate what is considered to be a preferred embodiment of the invention, it is not intended to limit the invention to all of the details shown as there can manifestly be considerable modification and change without departing from the spirit of the invention.

Having thus described the invention what is claimed is:

1. A steam generator comprising a central header or chamber having a water inlet, a steam outlet, and a plurality of series of ports in its side wall, a plurality of superposed units each including a sleeve, fitted about the central header, and an outer tubular member surrounding said sleeve and connected thereto by a series of radiating conduits, each sleeve having ports communicating with one of the series of ports in the side of the central header, and means for conducting water from each tubular member to the central header.
2. A steam generator comprising a central header or chamber provided with an exterior abutment adjacent its lower end, and having a water inlet, a steam outlet, and a plurality of series of ports in its side wall, a plurality of superposed units each including a sleeve fitted about the central header, an outer tubular member surrounding said sleeve and a series of tubes connecting said sleeve and member, each sleeve having ports communicating with one of the series of ports of the central header, means for conducting water from each tubular member to the central header, and means for holding the sleeve of said units in contact with each other and against the abutment on the central header.
3. A steam generator comprising a plurality of superposed units, each including an annular tubular member having a plurality of inwardly and outwardly radiating tubes

connected therewith, a sleeve common to all of the inwardly radiating tubes, and a sleeve at the outer end of each outward radiating tube, a central header extending through all of said inner sleeves and provided with a water inlet, a steam outlet and ports communicating with ports in each of said inner sleeves, means for holding the several units together with the outer sleeves thereof in communicating relation, and conduits connecting the outer sleeves of the lowest unit with the central chamber.

4. A steam generator comprising a central header or chamber having an exterior abutment adjacent its lower end, and provided with a water inlet, a steam outlet and a plurality of series of ports in its side wall, a plurality of superposed units, each including an annular, tubular, member having a plurality of inwardly and outwardly radiating tubes connected therewith, a sleeve common to all of the inwardly radiating tubes and a sleeve at the outer end of each outward radiating tube, said inner sleeve surrounding the central header above the abutment thereon and each communicating with one of the series of ports in the side wall of said chamber, means for holding said sleeves about the central header in contact with each other and with the said abutment, means connecting the superposed outer sleeves, and conduits connecting each of said series of outer sleeves with the central header.

5. In a steam generator, the combination of a central header or chamber provided with an exterior abutment near its lower end and having a water inlet, a steam outlet and a plurality of series of lateral ports, a plurality of units each comprising a sleeve fitted about the central header and an annular, tubular member connected to said sleeve by a series of radiating tubes, the meeting ends of adjacent sleeves having overlapping portions, packing rings arranged between said sleeves, means for holding said sleeves in contact with each other and against said abutment, and means for conducting water from the outer member of each unit to the central header.

In testimony whereof I have hereunto set my hand.

THOMAS J. McDONALD.
